[57] CLAIM

The ornamental design for a cooking grill or similar
article, substantially as described and shown.

DESCRIPTION

FIG. 1 is a top plan view of a cooking grill showing our
new design;

FIG. 2 is a perspective view thereof;

FIG. 3 is a front elevational view thereof;

FIG. 4 is a side elevational view thereof, the other side
being a mirror image;

FIG. 5 is a side elevational view thereof with the grate
in a raised position; and

FIG. 6 is a side elevational view thereof with the grate
in an upright position.
